(57) **CLAIM**

The ornamental design for a three-wheeled electric scooter with improved stability, as shown and described.

DESCRIPTION

FIG. 1 is a first perspective view of a three-wheeled electric scooter with improved stability, showing our new design; FIG. 2 is a second perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right side elevational view thereof; and, FIG. 8 is a left side elevational view thereof.

The broken lines shown in the drawings depict portions of the three-wheeled electric scooter with improved stability that form no part of the claimed design. The grayscale shading of the drawings depict the shape of the three-dimensional surface and do not represent any particular colors.
